UNITED STATES PATENT OFFICE.

WILLIAM H. FORKER, OF MEADVILLE, PENNSYLVANIA, ASSIGNOR TO HIMSELF AND G. HEMLER, OF SAME PLACE, AND SAID HEMLER ASSIGNOR TO HENRY BALDWIN, JR., OF PHILADELPHIA, PENNSYLVANIA.

IMPROVEMENT IN CAR-COUPINGS.

Specification forming part of Letters Patent No. 44,484, dated September 27, 1864; antedated September 18, 1864.

To all whom it may concern:

Be it known that I, WILLIAM H. FORKER, of Meadville, in the county of Crawford and State of Pennsylvania, have invented a new and Improved Car-Coupling; and I do hereby declare that the following is a full, clear, and exact description of the same, reference being had to the accompanying drawings, making a part of this specification, in which—

Figure 1 is a longitudinal vertical section of my invention, taken in the line *x x*, Fig. 2; Fig. 2, a transverse vertical section of the same, taken in the line *y y*, Fig. 1.

Similar letters of reference indicate corresponding parts in the two figures.

This invention relates to an improved car-coupling of that class which are commonly termed "self coupling;" and it consists in the employment or use of a drop-pin connected by a joint to an arm pivoted at the upper part of the draw-head, and having a spring bearing against the under side of its back part, all being arranged in such a manner that an ordinary link or shackle in the draw head of the car may, on entering the draw-head of an adjoining car, engage itself with the drop-pin, and form a connection between the two cars, while the parts being few and combined, and arranged in a simple way, insure durability and prevent the liability of the coupling getting out of perfect working order.

To enable those skilled in the art to fully understand and construct my invention, I will proceed to describe it.

A represents a draw-head, the front part of which is of flaring form, and has a horizontal recess, *a*, made in it to receive the link or shackle *B*.

C is an arm, which may be constructed of wrought-iron, and is secured in the upper part of the draw-head by a pivot-bolt, *b*, on which it is allowed to work freely. The back part

of the arm *C*, beyond the pivot-bolt *b*, has a spring, *D*, bearing against its under side, and this spring has a tendency to keep the front part of said arm pressed down, so that it will bear or rest upon the draw-head, the latter having a groove in its upper surface to receive said arm, so that the top of the arm and top of the draw-head will be flush with each other.

To the front end of the arm *C*, at its under side, there is attached by a joint, *c*, a drop-pin, *D'*, which passes down into a recess, *d*, in the draw-head, said recess being in the form of a quarter-circle, as shown in Fig. 1, to admit of the pin *D'* being shoved back by the link or shackle *B*, when the latter is forced into the draw-head. The upper part of the pin *D'* has a projection, *e*, which, when the pin is forced back, bears against the arm *C*, and causes it to be forced upward, so that the link or shackle may pass behind the pin, the spring *D* forcing the pin down through the link or shackle after the latter has passed behind the former. When the link or shackle is subjected to the pull or draft, the pin *D'* bears against the front side, *f*, of the recess *d*. (See Fig. 1.)

The pin *D'* is raised so as to release the link or shackle by means of a cord or chain, *g*, attached to the front end of the arm *C*.

Having thus described my invention, what I claim as new, and desire to secure by Letters Patent, is—

The combination of the arm *C* and spring *D*, hinged drop-pin *D'*, and projection *e*, constructed and arranged as described, and operating in connection with the draw-head *A* and link or shackle *B*, in the manner and for the purposes specified.

WM. H. FORKER.
